RAILWAY TRAFFIC CONTROLLING
APPARATUS

Claude M. Hines, Pittsburgh, and Bernard E. O'Hagan, Swissvale, Pa., assignors to The Union Switch & Signal Company, Swissvale, Pa., a corporation of Pennsylvania

Application December 14, 1937, Serial No. 179,704

13 Claims. (Cl. 246—219)

Our invention relates to railway traffic controlling apparatus, and has for an object the provision of novel and improved apparatus for the protection of a railway switch operating motor against overload conditions, and which apparatus provides resetting thereof subsequent to an overload condition.

We shall describe five forms of apparatus embodying our invention, and shall then point out the novel features thereof in claims.

Figs. 1, 2, 3, 4 and 5 of the accompanying drawings are diagrammatic views of specific forms of apparatus each form of which embodies our invention.

Similar reference characters refer to similar parts in each of the different views.

Referring to Fig. 1, the reference character S designates a railway track switch which is actuated by an electric motor M through the medium of a suitable switch operating mechanism SM, the motor M being here shown as a reversible direct current motor having an armature 5 and a field winding 6. The mechanism SM may be of any of the standard types, and is shown conventionally for the sake of simplicity. The switch S operates a circuit controller E comprising a contact 7—8 closed in all positions of the switch except in the extreme normal position, that is, in the position shown in Fig. 1, and a contact 7—9 closed in all positions of the switch except in the extreme reverse position, that is, in the position opposite that shown in Fig. 1.

The motor M is reversibly operated by means of a normal and a reverse operating circuit, which circuits are controlled by a direct current polarized relay WR. In Fig. 1, relay WR is provided with two operating windings 12 and 13. An auxiliary or overload relay OR is associated with relay WR for protecting the motor M under overload conditions in a manner to be later described. In this form of the invention, the relay OR is a direct current neutral relay provided with two energizing windings 14 and 15.

The relay WR is controlled over a pole changer CL which may be located at any convenient point such as an operator's office remote from the track switch S. The pole changer CL may be actuated by a switch lever of an interlocking machine. The control of relay WR is effected from the pole changer CL over a pair of control line wires 10 and 11 which are reversibly connected with a source of direct current such as a battery 10 through the medium of the pole changer CL. The arrangement is such that the battery 10 is connected with the control wires 10 and 11 to

supply current of one polarity, which we shall term normal polarity, when the pole changer CL is set at the position indicated by the solid lines, and to supply current of the other polarity, which we shall term reverse polarity, when the pole changer is set at the position indicated by the dotted lines. The winding 12 of relay WR is permanently connected across the control wires 10 and 11, but the winding 13 of relay WR is connected across the wires 10 and 11 over pole changing contact fingers 16 and 17 of the overload relay OR. When relay OR is deenergized and released so that the contact fingers 16 and 17 are in engagement with back contacts 18 and 19, respectively, the windings 12 and 13 of relay WR are connected with the control wires 10 and 11 as required for the magnetic fluxes created thereby to add their effects, and relay WR is effectively energized and picked up to close front neutral contacts 20 and 21, as well as to operate polar contact fingers 22 and 23. With current of normal polarity supplied to the control wires 10 and 11, and the relay OR released, the energization of relay WR is of normal polarity, and the polar contact fingers 22 and 23 are shifted to the left-hand position, that is, to the position shown in Fig. 1. With current of reverse polarity supplied to the wires 10 and 11 and relay OR released, the energization of relay WR is of the reverse polarity, and the polar contact fingers 22 and 23 are shifted to the right-hand position, that is, the position opposite that shown in Fig. 1.

Under conditions that cause the relay OR to be effectively energized and picked up so that the contact fingers 16 and 17 are in engagement with front contacts 24 and 25, respectively, the connection of winding 13 of relay WR is reversed, and the energization of winding 13 opposes that of winding 12 and relay WR is deenergized and released, opening its front neutral contacts 20 and 21, the polar contact fingers 22 and 23 preferably remaining in the position to which they were last moved.

When relay WR is energized with current of normal polarity, a normal motor operating circuit is formed from the B terminal of a current source, such as a battery not shown, over polar contact finger 22 in its normal position, front neutral contacts 20 and 21 in multiple, motor 50 armature 5, a resistor R to be referred to later, polar contact finger 23 in its normal position, contact 7—8 when closed, field winding 6, and to the C terminal of the current source. With motor M thus supplied with current, it is rotated in a

direction as required to move the track switch S to the normal position. When relay WR is energized with current of reverse polarity, a reverse motor operating circuit is formed from B 5 terminal over polar contact finger 23 in its reverse position, resistor R, motor armature 5, front neutral contacts 20 and 21 in multiple, polar contact finger 22 in the reverse position, contact 7-9, field winding 6, and to the C terminal, 10 This time, the flow of current through the motor armature 5 is reversed and the motor is operated in the direction as required to move the track switch to its reverse position.

The resistor R is common to both the normal 15 and the reverse motor operating circuits. The resistor R is preferably constructed of material having a relatively high positive temperature coefficient of resistance, such as nickel or iron. The winding 14 of relay OR is connected across 20 the resistor R over wires 26 and 27. It follows that the motor operating current flows through the resistor R and the winding 14 in multiple, the magnitude of the current flowing in the winding 14 depending upon the relative value 25 of the resistor R. The parts are so constructed and proportioned that, when the motor current flowing to resistor R and the winding 14 in multiple does not exceed that required to operate motor M and in turn the track switch S under usual 30 operating conditions, the potential drop across resistor R is relatively low and the energization of winding 14 is insufficient to pick up the relay OR. However, under overload conditions such as occur in the event the track switch S is obstructed, 35 the motor current is relatively large and the resistor R quickly heats up to materially increase its resistance so that the potential drop across the resistor R soon exceeds a predetermined value and the winding 14 of relay OR is 40 energized sufficiently to pick up that relay, closing its front neutral contacts. The parts are further so proportioned that surges of current which are high in value but of relatively short 45 duration, such as starting and reversal surges, are not effective to pick up the relay OR.

It is clear that under usual operating conditions the relay WR follows as to normal and reverse positions the corresponding movements of the pole changer CL, and the relay WR in turn causes corresponding normal and reverse operations of the motor M to actuate the track switch S, the operation of motor M being terminated at the extreme position of the track switch through the medium of controller E. In the event the track switch meets an obstruction so that an overload on the motor M occurs, the potential drop across the resistor R soon exceeds a predetermined value and relay OR is picked up in response to the increased energization of winding 14. Relay OR, on picking up, shifts the pole changing contact fingers 16 and 17 from engagement with the respective back contacts to engagement with the respective front contacts, causing a reversal in the connection of winding 60 13 of relay WR, with the result that relay WR is deenergized and released, opening its front neutral contacts 20 and 21 to interrupt the motor operating circuit. When relay OR is picked up, the front contact 28 is closed and completes a stick circuit easily traced by which the winding 65 15 is connected across control wires 10 and 11 so that the relay OR is retained energized and held picked up by current supplied from battery 70 over the pole changer CL and the wires 10 and 75 11, notwithstanding the fact that winding 14 of

relay OR is deenergized when the motor operating circuit is interrupted. It follows that an overload condition which causes the relay OR to be picked up to interrupt the motor operating circuit also completes a connection for the relay 5 OR with the control line wires 10 and 11 so that the relay OR is retained energized and picked up, and the relay WR is held deenergized and the overloaded circuit held open until such time as 10 the relay OR is reset.

After such an interruption due to an overload condition, the apparatus can be reset by the pole changer CL being operated. Operation of the pole changer CL causes a reversal in the polarity 15 of the current supplied to the control wires 10 and 11, and the energization of winding 15 of relay OR is reversed. During the interval the magnetic flux passes through zero, relay OR is released, opening the front contact 28 by which the winding 15 is connected with the control 20 wires 10 and 11. With relay OR released, the connection of winding 13 of relay WR is changed so that the two windings 12 and 13 are now in agreement and the relay WR at once responds to the new setting of the pole changer CL. Since 25 the current supplied to the wires 10 and 11 is opposite that supplied to the wires 10 and 11 prior to the overload condition, the relay WR reverses its position and causes the motor M to move the switch S back to the position it occupied prior to the overload condition.

With the apparatus of Fig. 1, there are two alternative arrangements for the relay WR. The preferred arrangement is to have the windings 12 30 and 13 so proportioned that both windings must be energized to operate the relay. This arrangement assures the detection of a fault in the control circuit at the first operation after a fault occurs. A second arrangement is to have the windings 12 and 13 so proportioned that energization of either winding alone is effective to 35 operate the relay.

There is a third arrangement for relay WR that would be at times useful. This third arrangement would be to omit the winding 12 and 40 operate the relay by winding 13 alone. Under this arrangement, the operation of the apparatus would be modified to the extent that, when an overload occurs and the overload relay OR picks up reversing the position of its contact fingers 16 45 and 17, the relay WR is reversed and the motor M is operated at once to return the switch to the position it occupied prior to the overload condition. To regain control, the operator would reverse the position of the pole changer CL to release relay OR and to bring the pole changer CL 50 into agreement with the relay WR and the switch.

In Fig. 2, the track switch S is operated by the motor M through the medium of a switch operating mechanism SM, the same as in Fig. 1, except for the fact the switch mechanism of Fig. 2 would preferably be of the dual type having the usual dual selector lever (not shown). The controller E of Fig. 2 is operated from the track 60 switch S, the same as in Fig. 1. The motor circuits are governed by a relay WR1, which relay is a direct current polarized relay having a single operating winding 30. For protection to the motor under overload conditions, a slow acting direct current neutral relay OR1 is provided. The relay WR1 is controlled over the remote pole changer CL and control wires 10 and 11, the same as in Fig. 1. One terminal of winding 30 of relay WR1 is connected directly with the control wire 10, while the other terminal of winding 30 70 75

is connected with control wire 11 over a normally closed contact 31 operated by the dual selector lever of the switch mechanism SM and a back contact 32 of the overload relay OR1. It follows that, as long as relay OR1 is deenergized and released and the dual selector is set for power operation closing contact 31, the relay WR1 follows as to position the movements of pole changer CL. With relay WR1 energized by current of normal polarity, a normal motor operating circuit is formed from B terminal over front neutral contacts 33 and 34 in multiple, polar contact finger 35 in its normal position, a resistor R1, motor armature 5, polar contact finger 36 in its normal position, contact 7-8 when closed, field winding 6 and C terminal. With relay WR1 energized by current of reverse polarity, a reverse motor operating circuit is formed from B terminal over front neutral contacts 33 and 34 in multiple, polar contact finger 36 in its reverse position, motor armature 5, resistor R1, polar contact finger 35 in its reverse position, contact 7-9, field winding 6, and to the C terminal.

The resistor R1 is similar in construction to resistor R of Fig. 1, and is common to both motor operating circuits. The operating winding 37 of relay OR1 is connected in multiple with resistor R1 over front contacts 38 and 39 of relay WR1, as will readily be understood by an inspection of Fig. 2. The parts are so proportioned that the potential drop across resistor R1 caused by the usual motor operating current produces a flow of current in winding 37 insufficient to energize relay OR1 at its pick-up value, but that an overload current flowing in the motor circuit causes the resistor R1 to quickly heat up, increasing its resistance to the point where the potential drop across the resistor is above a predetermined value and relay OR1 is energized sufficiently to pick up and close the front contact 40. Furthermore, as pointed out in Fig. 1, the parts are so proportioned and adjusted that starting and reversal surges of current do not last for a sufficient period to cause relay OR1 to be picked up.

When relay OR1 is picked up, opening its back contact 32, the winding 30 of relay WR1 is disconnected from the wires 10 and 11, and relay WR1 is released, interrupting the motor circuit at front contacts 33 and 34. When relay WR1 is released, one terminal of winding 37 of relay OR1 is connected with the control wire 10 over back contact 41 of relay WR1 and a current limiting resistor 42, and the other terminal of winding 37 is connected with control wire 11 over back contact 42 of relay WR1 and the front contact 40 of relay OR1. Consequently, with the apparatus constructed as disclosed in Fig. 2, an overload condition on the motor M that raises the potential drop across resistor R1 above a predetermined value causes relay OR1 to be picked up to deenergize relay WR1, and relay WR1 upon releasing interrupts at its front neutral contacts the overloaded motor circuit. The relay WR1, upon releasing, also shifts the connection for winding 37 of relay OR1 to the control wires 10 and 11 so that relay OR1 is retained energized by current supplied over a stick circuit comprising the pole changer CL, the line wires 10 and 11 and its own front contact 40 and winding 37, with the result the relay WR1 remains deenergized, holding the overloaded motor circuit open.

The operator can regain control of relay WR1 subsequent to an overload condition by shifting

the pole changer CL to reverse the polarity of the current supplied to the wires 10 and 11, the relay OR1 being released during the reversal of its energization opening its own front contact 40 interposed in the connection of winding 37 with the control wires. When relay OR1 is released, the relay WR1 is again connected with the control wires 10 and 11 and is operated to the position corresponding to the polarity of the current supplied to the control wires, so that the motor M is operated to move the switch back to the position it occupied prior to the overload condition.

In case the dual selector of the switch machine SM of Fig. 2 is set for hand operation of switch S, the shifting of contact 31 deenergizes the relay WR1, and the shifting of the normally open contact 43 of the dual selector completes the connection of winding 37 to the control wires 10 and 11, so that relay OR1 is picked up, closing its stick circuit at front contact 40, over which it is then retained energized. Consequently, when the dual selector is returned to normal after hand operation, the relay WR1 remains deenergized and motor M is inactive until such time as the operator at the remote office reverses the pole changer CL to cause the relay OR1 to be released.

In Fig. 3, the apparatus is similar to that of Fig. 2 except the overload relay OR2 is provided with two energizing windings 56 and 57, and is not controlled over contacts of the motor operating relay WR2.

The winding 56 of relay OR2 is connected in multiple with resistor R2, which resistor is common to both motor operating circuits, as will be readily understood by an inspection of Fig. 3. The winding 57 of relay OR2 is normally short-circuited over its own back contact 58 to provide slow pick-up characteristics. To energize winding 57 at times from the control wires 10 and 11, one terminal of winding 57 is connected with wire 10 over a current limiting resistor 59, while the other terminal of winding 57 is connected with wire 11 over transfer contact 60 and front contact 61 of a continuity transfer contact of relay OR2.

The parts are so proportioned that an overload current flowing in resistor R2 causes it to heat up, raising its resistance, and in turn the potential drop across the resistor, so that the potential drop across the resistor exceeds a predetermined value, with the result that winding 56 of relay OR2 is energized to the pick-up value of the relay, and relay OR2 is picked up. Overload relay OR2, on picking up, opens the connection of winding 62 of relay WR2 with wire 11 at the back contact 63 of relay OR2. Relay WR2, when thus deprived of energizing current, quickly releases, interrupting the motor operating circuit at its front neutral contacts 64 and 65. It is to be noted that the short circuit connection for winding 57 of relay OR2 at back contact 58 causes the relay OR2 to be slow acting, and operation of relay OR2 due to the starting and reversal surges of current is avoided. When relay OR2 is picked up, the closing of contact 60-61 completes the connection of winding 57 across the control wires 10 and 11, and relay OR2 is retained energized by a stick circuit comprising the pole changer CL, wires 10 and 11, front contact 60-61 and winding 57, subsequent to the interruption of the motor circuit.

Operation of the pole changer CL of Fig. 3, subsequent to an overload condition, reverses the polarity of the current supplied to the control

wires, and relay OR2 is released during the reversal of its energization. With relay OR2 released, the connection of relay WR2 is restored and relay WR2 is in turn operated to the position corresponding to the new position of the pole changer, so that the motor M is operated to restore the track switch S to the position it occupied prior to the overload condition.

In Fig. 4, the motor M operates the track switch S through the medium of a switch operating mechanism SM, the same as in Fig. 1, the motor operating circuit being governed by a direct current polarized relay WR3 having a single operating winding 44. The normal and reverse motor circuits controlled by relay WR3 are similar to those described in Figs. 1 and 2, and it is thought unnecessary to repeat their description in detail, except to point out that the resistor R3 of Fig. 4 is common to both motor circuits.

Overload protection of motor M of Fig. 4 is accomplished through the medium of an overload relay OR3 having a single operating winding 45.

To control relay WR3 by the remote pole changer CL, one terminal of the winding 44 of relay WR3 is connected directly with the control wire 10, and the other terminal of winding 44 is connected with the wire 11 over back contact 46 of the overload relay OR3. It is clear that, as long as relay OR3 is deenergized and its back contact 46 closed, the relay WR3, and in turn the motor M, are responsive to operation of the pole changer CL.

The resistor R3 is preferably constructed and proportioned similarly to the resistor R of Fig. 1. One terminal of winding 45 of relay OR3 is connected at one end of the resistor R3 over transfer contact 47 and back contact 48 of the relay, while the other terminal of winding 45 is connected with the other terminal of resistor R3 over transfer contact 49 and back contact 50 of the relay. The parts are so proportioned and adjusted that the potential drop across resistor R3 caused by the usual operating current is less than that required to energize relay OR3 to the point where it picks up, but the larger value of current flowing in the motor circuit under overload conditions soon creates a potential drop across resistor R3 above a predetermined value and relay OR3 is energized sufficiently to pick up. The picking up of relay OR3 to open its back contact 46 causes the relay WR3 to become deenergized, and relay WR3 on releasing interrupts the motor circuit at the neutral front contacts 51 and 52. When relay OR3 is picked up, the connection of its winding 45 is shifted from resistor R3 to the control wires 10 and 11 through the medium of the front contacts 54 and 55. The connection from wire 10 to the left-hand terminal of winding 45 includes resistor 53, front contact 54 and the transfer contact 47, while the connection from wire 11 to the right-hand terminal of winding 45 includes front contact 55 and transfer contact 49. It follows that relay OR3, when once picked up, due to the potential drop created across resistor R3 by an overload current, is retained picked up by a stick circuit comprising the pole changer CL, control wires 10 and 11, front contacts 54 and 55 and winding 45.

Operation of the pole changer CL of Fig. 4 subsequent to an overload condition reverses the polarity of the current supplied to wires 10 and 11 and reverses the energization of relay OR3 which is released during the interval the magnetic flux passes through zero. With relay OR3

released, the connection of relay WR3 with the control wires is restored, and relay WR3 is operated to the position corresponding to the new position of the pole changer to cause motor M to actuate the switch back to the position it occupied prior to the overload condition. It will be understood, of course, that the apparatus of Fig. 3 is proportioned and adjusted so that starting and reversal current surges do not cause an operation of the overload relay OR3.

In Fig. 5, the switch S is operated by the motor M through the medium of a switch mechanism SM, the same as in the other cases, the mechanism SM in Fig. 5 being of the dual selector type, the same as in Fig. 2. The controller E1 of Fig. 5 comprises two movable contact members 90 and 91. Contact member 90 makes engagement with a stationary contact 92 in all the positions of the switch except the full normal position, and contact member 91 engages a stationary contact 93 in all the positions except the full reverse position.

A polarized relay WR4 controls the motor M through the medium of two contactors NC and RC, the relay WR4 in turn being governed over the control wires 10 and 11 from the remote pole changer CL. The contactor NC is governed by relay WR4 by virtue of a circuit which includes the normal polar contact 94 of relay WR4, contact 90-92 of controller E1, winding of contactor NC, and the back contact 95 of an associated overload relay OR4. The control circuit of contactor RC involves reverse polar contact 66 of relay WR4, contact 91-93 of controller E1, winding of contactor RC, and the back contact 95 of relay OR4. With contactor NC energized, the normal motor operating circuit is completed at front contact 67 of contactor NC and back contact 68 of contactor RC, as will be readily understood by an inspection of Fig. 5. With contactor RC energized, the reverse motor operating circuit is completed at front contact 69 of contactor RC and back contact 96 of contactor NC. A resistor R4 is common to both motor operating circuits, the same as in other forms of the invention.

The overload relay OR4 is provided with a single operating winding 71 which is connected across the resistor R4 over back contacts of the relay. To be specific, the right-hand terminal of winding 71 is normally connected with the left-hand terminal of resistor R4 over transfer contact 97 and back contact 73 of the relay and a normally closed contact 74 of the dual selector lever of the mechanism SM. The left-hand terminal of winding 71 is connected over transfer contact 75 and back contact 76 of the relay with the right-hand terminal of resistor R4. The parts are so proportioned that the potential drop across resistor R4 caused by the usual motor operating current does not shunt sufficient current through winding 71 to pick up the relay OR4. An overload current flowing in the motor circuit causes resistor R4 to heat up, however, raising its resistance so that sufficient current is shunted through winding 71 to pick up the overload relay.

With the relay OR4 picked up, the connection for its winding 71 is shifted to the control wires 10 and 11. The connection includes transfer contact 97 and front contact 77 on one side, and the transfer contact 75 and the front contact 78 on the other side. When overload relay OR4 is picked up to open its back contact 95, the contactor NC or RC, as the case may be, is de-

energized to interrupt the overloaded motor circuit. With the winding of relay OR4 shifted to the control wires 10 and 11, the overload relay is retained energized by the stick circuit including the pole changer, and the overloaded motor circuit is held open until such time as the pole changer CL is shifted to cause the release of relay OR4.

With the dual selector shifted for hand operation, a connection is closed at the contacts 80 and 81 whereby the winding 71 of relay OR4 is connected with the control wires 10 and 11, and relay OR4 is picked up and then retained energized over the stick circuit including its 15 front contacts 77 and 78. Thus, when the dual selector is returned to its normal position subsequent to hand operation, the overload relay OR4 remains energized so that the operator to regain control of the switch must first shift the 20 pole changer CL to cause the release of the overload relay.

Although we have herein shown and described only five forms of apparatus embodying our invention, it is understood that various changes 25 and modifications may be made therein within the scope of the appended claims without departing from the spirit and scope of our invention.

Having thus described our invention, what we 30 claim is:

1. In combination, a reversible electric motor, a normal and a reverse operating circuit for the motor, control means including a current source and a manually operable pole changer as well 35 as a pair of control wires for selectively governing said motor operating circuits, a resistor common to both of the motor circuits, a neutral relay having a winding connected across said resistor, said relay and resistor proportioned and adjusted 40 to pick up the relay only when an overload current flows through the resistor for a predetermined interval, means controlled by the relay when picked up to interrupt the overloaded motor circuit; and a stick circuit for said relay comprising said current source, pole changer and 45 control wires as well as a front contact and a winding of the relay for holding the overloaded circuit open until the pole changer is operated.

2. In combination, a reversible electric motor, 50 an operating circuit means for said motor, a manually operable pole changer for reversibly governing the supply of current to said circuit means for operating the motor, a resistor having a positive temperature coefficient interposed in 55 said circuit means, a relay having a winding connected across said resistor, said relay adjusted to pick up only when an overload current flows through said resistor and the resistor heats up to increase its resistance so that the potential drop across the resistor exceeds a predetermined 60 value, means controlled by said relay when picked up for interrupting said motor circuit means, and a stick circuit for said relay including said pole changer and a winding of the relay as well as a front contact of the relay.

3. In combination, a track switch having operatively connected therewith a reversible electric motor, a normal and a reverse operating circuit for the motor, a direct current polarized relay 65 for selectively governing said circuits, a control circuit for said relay including a pole changer and a pair of control wires, a neutral overload relay having a winding common to both said motor operating circuits, said overload relay adjusted to pick up only when an overload current 70

flows in a motor operating circuit for a given period, means controlled by the overload relay when picked up to interrupt the overloaded motor circuit, and a stick circuit for said overload relay comprising said pole changer and said 75 control wires as well as a front contact and a winding of the relay for holding the overloaded circuit open until the pole changer is operated to reverse the polarized relay and operate the motor to move the track switch to the position 10 it occupied prior to the overload condition.

4. In combination, a reversible electric motor, a direct current polarized relay, a control circuit including a pole changer for controlling said relay, a normal motor operating circuit including 15 a normal polar contact and a front neutral contact of said relay, a reverse motor operating circuit including a reverse polar contact and a front neutral contact of said relay, a resistor having a positive temperature coefficient common to both of said motor circuits, a neutral relay having a winding connected across said resistor and which relay is picked up only when an overload current flows in a motor circuit and the potential drop across said resistor exceeds a 20 predetermined value, means including a front contact of said neutral relay operative to deenergize said polarized relay for interrupting the overloaded motor circuit, and a stick circuit for 25 said neutral relay connected with said control 30 circuit for holding the overloaded circuit open until the pole changer is operated.

5. In combination, a reversible electric motor, a direct current polarized relay, a pole changer, circuit means including said pole changer for 35 reversibly energizing said polarized relay, a single winding slow acting overload relay having a back contact interposed in said circuit means for at times deenergizing said polarized relay, motor operating circuit means including 40 normal and reverse polar contacts as well as a front neutral contact of said polarized relay, a resistor characterized by a positive temperature coefficient interposed in said motor operating circuit means, means including a contact of said polarized relay to connect said single winding of said slow acting relay across said resistor to pick up said slow acting relay when an overload current flows in said motor operating circuit means to deenergize the polarized relay for 45 interrupting the operating circuit means, and a stick circuit for said slow acting relay including said pole changer, another contact of said polarized relay and said single winding of the relay.

6. In combination, a reversible electric motor, a direct current polarized relay, a pole changer, a control circuit including said pole changer and a winding of said relay for reversibly energizing said relay, a slow pickup slow release neutral relay having a back contact interposed in said 55 control circuit, motor operating circuit means including normal and reverse polar contacts as well as a front neutral contact of said polarized relay, a resistor characterized by a positive temperature coefficient interposed in said motor operating circuit means, means to connect a winding of said neutral relay across said resistor to pick up the neutral relay when an overload current flows in the motor operating circuit and the potential drop across the resistor exceeds a predetermined 60 value to deenergize the polarized relay for interrupting the overloaded motor circuit, means including a back contact of said polarized relay and another resistor to connect a winding of the neutral relay with said control circuit to retain ener- 65

75

gized the neutral relay for holding the polarized relay deenergized and the overloaded circuit open, and a front contact of said neutral relay interposed in the connection of the winding of the 5 neutral relay to said control circuit to release the neutral relay when the pole changer is operated.

7. In combination, a reversible electric motor, a direct current polarized relay provided with two windings, a direct current neutral relay provided 10 with two windings, a pole changer for reversibly connecting a pair of control wires with a source of direct current, a first means to connect one of the windings of said polarized relay across said control wires, a second means including pole 15 changing front and back contacts of said neutral relay to connect the other winding of said polarized relay across said control wires, said windings of the polarized relay connected to aid when said neutral relay is released and to oppose each other 20 when the neutral relay is picked up, motor operating circuit means including normal and reverse polar contacts as well as a front neutral contact of said polarized relay, a resistor having a positive temperature coefficient interposed in said motor 25 operating circuit means, means to connect one of the windings of said neutral relay across said resistor to pick up said neutral relay when the current flowing through said resistor exceeds a predetermined value and the potential drop across 30 the resistor exceeds a given value, and means including a front contact of the neutral relay to connect the other winding of said neutral relay across the control wires.

8. In combination, a reversible electric motor, 35 a direct current polarized relay, a neutral relay, motor operating circuit means including normal and reverse polar contacts as well as a front neutral contact of said polarized relay, a pair of control wires, a pole changer for connecting a source 40 of direct current with said control wires, means including a back contact of said neutral relay to connect a winding of the polarized relay across said control wires to reversibly energize the polarized relay for operating the motor in response to 45 operation of said pole changer, a resistor interposed in said motor operating circuit means, means including a front neutral contact of the polarized relay to connect a winding of the neutral relay across said resistor for picking up said 50 neutral relay in response to an overload current flowing in the motor operating circuit to deenergize the polarized relay and interrupt the motor operating circuit, and means including a back contact of the polarized relay and a front contact 55 of the neutral relay to connect the winding of said neutral relay across said control wire to retain the motor operating circuit interrupted until the pole changer is operated.

9. In combination, a reversible electric motor, 60 a direct current polarized relay, a neutral relay, motor operating circuit means including normal and reverse polar contacts as well as a front neutral contact of said polarized relay, a pair of control wires, a pole changer for connecting a source 65 of direct current with said control wires, means including a back contact of the neutral relay to connect a winding of the polarized relay across said control wires, a resistor having a positive temperature coefficient interposed in the motor 70 operating circuit means, means to connect a winding of the neutral relay across said resistor including a back contact of the neutral relay and arranged to pick up said neutral relay when the voltage drop across said resistor exceeds a predetermined value for deenergizing said polarized 75

relay to interrupt the motor operating circuit, and means including a front contact of the neutral relay to connect its winding across said control wires to retain the motor operating circuit interrupted until the next operation of the pole 80 changer.

10. In combination, a reversible electric motor, a direct current polarized relay, a neutral relay, motor operating circuit means including normal and reverse polar contacts as well as a front neutral contact of the polarized relay, a pair of control wires, a pole changer for connecting a source of direct current with said control wires, means including a back contact of the neutral relay to connect a winding of the polarized relay across 10 said control wires, means controlled by the polarized relay when energized to associate a winding of the neutral relay with said motor operating circuit means to pick up the neutral relay when an overload current flows in the motor and deenergize the polarized relay to interrupt the overloaded motor circuit, other circuit means controlled by the polarized relay when deenergized to connect a winding of the neutral relay across 15 the control wires to hold the overloaded motor circuit open, and a front contact of the neutral relay interposed in said other circuit means to restore the relays by an operation of the pole 20 changer.

11. In combination, a reversible electric motor, 25 a direct current polarized relay, a neutral relay, motor operating circuit means including normal and reverse polar contacts as well as a front neutral contact of the polarized relay, a pair of control wires, a pole changer for connecting a source 30 of direct current across the control wires, means including a back contact of the neutral relay to connect a winding of the polarized relay across said control wires for governing the polarized relay by operation of the pole changer, means including a back contact of the neutral relay to associate a winding of the neutral relay with the motor operating circuit means for picking up the neutral relay when an overload current flows in the motor for a predetermined interval, and a 35 stick circuit for the neutral relay including the winding and a front contact of the relay as well as said control wires and the pole changer.

12. In combination, a reversible electric motor, a direct current polarized relay, a neutral relay, 40 a manually operable selector having a first and a second position and normally set at its first position, a control circuit including a pole changer and a pair of control wires, means including a contact of the selector closed at its first position 45 and a back contact of the neutral relay to connect a winding of the polarized relay across said control wires to operate the polarized relay by said pole changer, motor operating circuit means including normal and reverse polar contacts as 50 well as a front neutral contact of the polarized relay, a pick-up circuit to associate a winding of the neutral relay with the motor operating circuit means to pick up the neutral relay in response to an overload current flowing in the motor to interrupt such overloaded motor circuit by deenergizing the polarized relay, a stick circuit to connect the winding of the neutral relay across the control wires to hold the overloaded circuit open until the pole changer is next operated, and other 55 circuit means including a contact of said selector closed at its second position to connect the winding of the neutral relay across the control wires to hold the neutral relay energized by said stick circuit and the polarized relay deenergized 60 subse- 75

quent to an operation of the selector to its second position and back to its first position until the pole changer is operated.

13. In combination, a current source, a pair of control wires, a pole changer for reversibly supplying current from said source to said wires at one end, a direct current polarized relay having a winding connected with the wires at said other end for reversibly energizing said relay, a reversible electric motor having a normal and a reverse operating circuit controlled by said relay, a resistor having a positive temperature coefficient common to both said motor circuits, a neutral relay having a winding connected across

15 said resistor, said neutral relay adjusted to pick up only when a motor overload current flows through said resistor and the resistor heats up to increase its resistance so that the potential drop across the resistor exceeds a predetermined value, means including a contact of said neutral relay effective when the neutral relay is picked up to interrupt the overloaded motor circuit, and a stick circuit for said neutral relay to connect a winding of that relay across said control wires at said other end for holding said overload relay 10 energized and to assure release of the overload relay when the pole changer is next operated.
